UNITED STATES PATENT OFFICE.

FREDERIC P. GATES, OF WEST HARTFORD, CONNECTICUT, ASSIGNOR TO THE FULLER-GATES COMPANY, OF HARTFORD, CONNECTICUT, A CORPORATION OF CONNECTICUT.

SNAP SWITCH.

Application filed February 7, 1924. Serial No. 691,182.

My invention relates to the class of snap switches wherein the switch member or blade is given a sudden snapping movement by changing the location of the point of attachment of the actuating spring, and an object of my invention, among others, is the provision of a mechanism of this type that shall be extremely simple and inexpensive in construction, particularly efficient in operation, and one in which the several parts may be interlocked to retain them in assembled condition.

One form of switch embodying my invention and in the construction and use of which the objects herein set out, as well as others, may be attained, is illustrated in the accompanying drawings, in which—

Figure 1 is a view in section through the supporting block for the switch mechanism on a plane indicated generally by the dotted line 1—1 of Figure 2.

Figure 2 is a bottom view of the switch with the bottom plate removed.

Figure 3 is a detail view illustrating a preliminary step in assembling the switch mechanism.

Figure 4 is a similar view, but illustrating a succeeding step in assembling such mechanism.

Figure 5 is another similar view, but illustrating another step in assembling the switch mechanism, Figures 3, 4 and 5 being shown in section on a plane generally indicated by the dotted line 3—3 of Figure 8, but the switch blade being shown in its normal operative position rather than in the position shown in Figure 8.

Figure 6 is a detail view of one of the supporting bars.

Figure 7 is a view in section through the supporting frame on a plane generally passing through one of the pivots of the switch blade supporting frame, this view illustrating the manner of attachment of the push button bars.

Figure 8 is a face view of the supporting frame and of the switch blade supporting frame, other parts also being shown but as cut in section.

Figure 9 is a top view of the switch.

My invention as illustrated and described herein comprises switch mechanism that is composed almost entirely of members cut or stamped from sheet metal and so ar-

ranged that they may be assembled by interlocking the parts one within another; thereby avoiding the use of screws and similar parts for securing the members together. Such mechanism as illustrated and described herein comprises a supporting frame preferably of generally rectangular shape, perfectly flat, and formed from sheet metal from which it may be stamped to shape as by means of dies. This frame comprises a top piece 9, a bottom piece 10 and side pieces 11. The top piece 9 has a guide notch 12 and the bottom piece has a bearing notch 13, both to receive a rocker frame as herein-after described, and the side parts each having a bearing lug 14 upon which parts of the mechanism to be hereinafter described are rotatably mounted. Notches 15 are also made in the outer edge of the bottom piece for the reception of supporting bars 16, which bars are also preferably notched for the reception of the bottom piece of the supporting frame, and they also are provided with openings 17 comprising a stop shoulder 18 at each end to limit the swinging movement of a switch blade supporting frame, which frame is formed from sheet metal, as are the bars 16 just described, said frame being of U-shape and comprising legs 19 joined by a cross piece 20. Each of the legs has rivet lugs 21 projecting from its outer edge and to which lugs pivot plates 22, one at each side of the frame are secured as by riveting the ends of the lugs. Each pivot plate has an opening constituting a bearing to receive one of the bearing lugs 14, each of said plates having an assembling notch 23 through which the bearing lug 14 is passed edgewise in the act of pivotally mounting the plates and securing them in position. Each of these notches is tapered from a wider dimension at the edge of the plate to a narrower dimension at the throat of the notch where it communicates with the bearing opening, said throat being of less width than the diameter of said opening so that the bearing lugs 14, after having been passed edgewise through said throat into the opening, will be held therein when the switch blade supporting frame is turned into its normal operative position. These pivot plates are both formed from sheet metal, in the same manner as hereinbefore described with respect to the

other parts, and a switch blade supporting plate 24, also formed in the same manner, is secured against the edge of one of the legs 19, a switch blade 25 being secured between said supporting plate and the pivot plate on this side of the structure, and as shown in Figure 2 of the drawings. The end of the switch blade supporting frame is located in the openings 17 and is caused, in the swinging movement of this frame, to strike the shoulders 18 that form stops to limit such movement of said frame.

A rocker frame 26 is also formed from sheet metal of the general shape of a four-sided figure, with top, bottom and side pieces, the bottom piece having a bearing notch 27 that receives the bottom piece 10 of the supporting frame, and as shown in Figures 3, 4 and 5 of the drawings, said bottom piece constituting the bearing for the rocker frame. The top piece 28, as to its outer edge, is curved substantially on the arc of a circle having the bottom of the notch 27 approximately as its center, this edge of said top piece fitting into the guide notch 12 in the supporting frame, and as shown in Figure 8 of the drawings. An actuating spring 29 is secured at one end to said top piece 28 and at its opposite end to the cross piece 20 of the switch blade supporting frame, as clearly shown in Figure 8 of the drawings.

Push button bars 30 are also formed from sheet metal, perfectly flat, and each has a slot 31 forming the bar into a link that engages by entry edgewise through a slot 32 into a hole 33 in the rocker frame 26. This hole is larger in diameter than the width of the slot 32 and the piece closing the outer end of the slot 31 is of a width substantially equal to the diameter of the hole 33 so that when said end piece is located within said hole and the bar 30 is swung to its engaged position said bar is held from disengagement from the rocker frame. There is a push button bar attached to each edge of said rocker frame, and each of said bars has a push button 34 secured to its outer end. Each push button has a recess 35 in its under surface to receive the upper edge of the rocker frame in its swinging movement, and this permits the buttons to be set well down on the bars 30 without interfering with the movement of said rocker frame.

It will be noted that every part thus far described, with the exception of the spring 29, switch blade 25 and the push buttons 34, is formed from sheet metal all of substantially the same thickness, all perfectly flat, and that, therefore, these parts may be rapidly produced in large quantities at a very low cost.

The switch blade supporting frame is of U-shape to enable it to be engaged within the opening in the rocker frame by insertion

of one of the legs 19 through said opening to locate the cross piece 20 in said opening. The throat of the assembly notch 23 being of less width than the diameter of the bearing opening, as hereinbefore described, will cause the switch blade supporting frame to be held in place after the flat lugs 14 have been passed edgewise through said throat and said frame has been turned to its normal operative position, as shown in Figure 7 of the drawings.

In assembling the structure the switch blade supporting frame is engaged with the rocker frame by passing one of the legs of the former through the opening in the latter, and both of said frames are then engaged with the supporting frame by placing the rocker frame with its notch 27 in engagement with the bottom piece 10 of the supporting frame, passing one end of the switch blade 25 through the opening in the supporting frame and engaging the top piece 28 of the rocker frame in the guide notch 12 in the supporting frame, the rocker frame being now swung substantially half way through the supporting frame. In this position of the parts the spring is not engaged with the switch blade supporting frame and the assembling notches 23 are located opposite the bearing lugs 14.

The rocker frame is now swung further in the same direction to the position shown in Figure 4 of the drawings, and the switch blade supporting frame is moved upwardly until the lugs 14 are located in their bearing openings in the switch blade supporting frame, in which position they are held while the rocker frame is swung in a reverse direction and to the position shown in Figure 5 of the drawings. This backward movement of the rocker frame causes the parts to assume the position shown in Figure 5 of the drawings, in which position the spring 29 may now be engaged with the switch blade supporting frame. After the spring has been thus engaged the rocker frame is again swung in a direction reverse to that just described and to the position shown in Figure 7, and the supporting bars 16 are placed in position with their notches engaging the notches 15 in the supporting frame. When thus placed the cross piece 20 of the switch blade supporting frame will be located in the openings 17 in the supporting bars, the parts now having the position shown in Figure 7 of the drawings. The push button bars 30 are now engaged with the rocker frame in the manner hereinbefore described and the structure is ready for insertion in the switch block.

This switch block 36 has a chamber 37 with side grooves 38 to receive the edges of the sides 11 of the supporting plate, this chamber also having end grooves 39 to receive the ends of the supporting bars 16 and

the structure is secured within the chamber 37 by engaging the edges of the supporting frame in the side grooves 38 and the ends of the supporting bars in the end grooves 39 and pushing the structure as an entirety into place in said chamber. A closing plate 40 is employed to cover the opening in the bottom of the block into the chamber therein, and this plate will also serve to retain 10 the switch mechanism in place.

Switch terminals 41, of any suitable construction to engage the switch blade 25 as the latter is rocked with its supporting frame in opposite directions on the pivots or bearing lugs 14, are secured upon and project from ledges in the chamber 37. These terminals are connected by suitable conductors, as screws 42, with wire terminals 43 secured to the upper side of the block 20 and having any ordinary and suitable means for attachment of wires thereto.

The switch blade 25, as hereinbefore described, is secured between the plates 22 and 24 and in doing this rivets are made use of, such rivets extending through both of said plates and through the switch blade which may be of any ordinary form and construction.

In accordance with the provisions of the 30 patent statutes I have described the principles of operation of my invention, together with the device which I now consider to represent the best embodiment thereof; but I desire to have it understood that the device shown is only illustrative and that the invention may be carried out by other means and applied to uses other than those above set out.

I claim—

40 1. A switch including switch mechanism comprising a flat rectangularly shaped supporting frame formed from a single piece of sheet metal and including side pieces having integral bearing lugs projecting therefrom, a rocker frame located in the opening in said supporting frame and seated for rocking movement upon the bottom piece of said supporting frame, a switch blade supporting frame mounted upon said lugs, a spring connecting said switch blade supporting frame and said rocker frame, and means for actuating said rocker mechanism.

55 2. A switch including switch mechanism comprising a flat rectangularly shaped supporting frame formed from a single piece of sheet metal and including side pieces having integral bearing lugs projecting therefrom, a rocker frame located in the opening in said supporting frame with one edge seated for rocking movement upon the bottom piece of said supporting frame and its opposite edge projecting into a guide slot in the top piece of said supporting frame, a switch blade supporting frame mounted upon said lugs, a spring connecting said switch

blade supporting frame and said rocker frame, and means for actuating said rocker frame.

3. A switch including switch mechanism comprising a flat rectangularly shaped supporting frame formed from a single piece of sheet metal and including side pieces having integral bearing lugs of a width greater than the thickness thereof, a switch blade supporting frame having bearings to receive 75 said lugs and with an opening into said bearing of a width less than the diameter of said bearing, a rocker frame operatively connected with said switch blade supporting frame, and means for operating said rocker frame. 80

4. A switch including switch mechanism comprising a flat rectangularly shaped supporting frame inclosing an opening and having integral lugs projecting from side pieces bounding said opening, a rocker frame 85 formed from a flat piece of sheet metal completely inclosing an opening and seated upon the bottom piece of said supporting frame for swinging movement crosswise thereof through the opening therein, a 90 switch blade supporting frame projecting through the opening in said rocker frame and mounted upon the lugs of the supporting frame, means for operatively connecting the switch blade supporting and rocker frames, and means for operating said rocker frame. 95

5. A switch including switch mechanism comprising a supporting frame having bearing lugs, a rocker frame completely inclosing an opening therein and supported upon one wall thereof for swinging movement in said supporting frame, a switch blade supporting frame mounted on said bearing lugs and open on one side for interlocking engagement in the opening in said rocker frame, and enclosed by the rocker frame, a spring connection between said switch blade supporting and rocker frames, and means for operating said rocker frame. 100 105 110

6. A switch including switch mechanism comprising a supporting frame having bearing lugs of less thickness than width, a switch blade supporting frame including side pieces, each having a bearing opening with a recess extending thereinto and having edges gradually converging to a throat leading into said bearing opening and of a width less than the diameter of said bearing opening, a rocker frame mounted in said 115 supporting frame and enclosing and operatively connected with said switch blade supporting frame, and means for operating said rocker frame. 120

7. A switch including switch mechanism comprising a polygonal supporting frame bounding an opening and having parallel side walls with a notch in a piece bounding said opening, a rocker frame seated for swinging movement on said bounding piece 125 130

and having a relatively wide notch with inclined side walls interengaging with said notch in said bounding piece, a switch blade supporting frame operatively connected with said rocker frame, and means for operating said rocker frame.

8. A switch including switch mechanism comprising a supporting frame bounding an opening with notches in bounding pieces located on opposite sides of said opening, a rocker frame seated for swinging movement on one of said bounding pieces and having a notch interengaging with the notch in said last mentioned bounding piece, the opposite side of the rocker frame engaging within the notch in the other of said bounding pieces for guiding movement therein, a switch blade supporting frame operatively connected with said rocker frame, and means for operating said rocker frame.

9. A switch mechanism including a supporting frame with mechanism operatively mounted therein, said supporting frame having a notch in one edge thereof, a supporting bar engaged within said notch, and a switch block having a groove to receive the ends of said supporting bar and grooves to receive the edges of said supporting frame.

10. A switch mechanism including a sup-

porting frame with mechanism operatively mounted therein, said supporting frame having a notch in an outer edge thereof, a supporting bar having a notch interlocked with the notch in said supporting frame, and a switch block having a chamber with grooves in opposite sides to receive the edges of said supporting frame and with oppositely disposed grooves to receive the ends of said supporting bar.

11. A switch mechanism including a supporting frame, a supporting bar having an opening with a notch extending therefrom, said notch receiving an edge of said supporting frame, a switch blade supporting frame projecting into said opening, and means for operating said switch blade supporting frame.

12. A switch mechanism including a supporting frame with mechanism mounted therein, a supporting bar in notched engagement with the edge of said supporting frame and extending crosswise thereof, and a switch block having a chamber with grooves in opposite walls to receive the edges of said supporting frame and also with grooves in its opposite walls to receive the ends of said supporting bar.

FREDERIC P. GATES.
